Primary Examiner — Elizabeth A. Albert(74) *Attorney, Agent, or Firm* — Seed Intellectual Property Law Group LLP(57) **CLAIM**

The ornamental design for a pen, as shown and described.

DESCRIPTION

FIG. 1 is a view of a pen rotated between a front and side elevation view showing my new design.

FIG. 2 is a front elevation view thereof.

FIG. 3 is a right side elevation view thereof, with the left side elevation view being a mirror image of the right side elevation view.

FIG. 4 is a rear elevation view thereof.

FIG. 5 is a top plan view thereof.

FIG. 6 is a bottom plan view thereof.

FIG. 7 is an enlarged top plan view thereof; and,

FIG. 8 is an enlarged bottom plan view thereof.

The broken lines in the figures illustrate environment only and form no part of the claimed design.
